Harry E. Soref and James Keith Marshall, Milwaukee, Wis., assignors to Master Lock Company, Milwaukee, Wis., a corporation of Wisconsin

Application February 4, 1935, Serial No. 55,241

Term of patent 14 years

To all whom it may concern:

Be it known that we, Harry E. Soref and James Keith Marshall, both citizens of the United States, residing in Milwaukee, in the county of Milwaukee and State of Wisconsin, have invented a new, original, and ornamental Design for Combination Padlocks, of which the following is a specification, reference being had to the accompanying drawing, forming part thereof.

In the drawing,

Fig. 1 is a front view of a combination padlock, showing my new design;

Fig. 2 is a rear view;

Fig. 3 is a side view, and

Fig. 4 is a top view.

We claim:

The ornamental design for a combination padlock, as shown.

HARRY E. SOREF.

JAMES KEITH MARSHALL.
